Primary Examiner — Messina L Smith*Assistant Examiner* — Aram Kwon(57) **CLAIM**

The ornamental design for a cover for an earbud charging case, as shown and described.

DESCRIPTION

FIG. 1 is a front, top, and left side perspective view of a cover for an earbud charging case, showing the new design; FIG. 2 is a top view thereof;

FIG. 3 is a front view thereof;

FIG. 4 is a bottom view thereof;

FIG. 5 is a back view thereof;

FIG. 6 is a left side view thereof; and,

FIG. 7 is a right side view thereof.

The broken lines illustrate portions of the cover for an earbud charging case that form no part of the claimed design.

1 Claim, 4 Drawing Sheets(56)
